UNITED STATES PATENT OFFICE.

ERICK H. ERICKSON, OF MINNEAPOLIS, MINNESOTA.

ARTIFICIAL LIMB.

SPECIFICATION forming part of Letters Patent No. 561,979, dated June 16, 1896.

Application filed January 28, 1896. Serial No. 577,097. (No model.)

To all whom it may concern:

Be it known that I, ERICK H. ERICKSON, a citizen of the United States, residing at Minneapolis, in the county of Hennepin and State of Minnesota, have invented certain new and useful Improvements in Artificial Limbs, of which the following is a specification.

This invention relates to artificial limbs; and it consists in the construction, combination, and arrangement of parts as hereinafter shown and described, and specifically set forth in the claims.

In the drawings, Figure 1 is a sectional side elevation of an artificial limb with my improvements embraced therein. Fig. 2 is a bottom plan view of the foot portion of the limb. Fig. 3 is an enlarged side view of the upper portion of the body of the limb and the slip-socket, and Fig. 4 is a sectional side elevation of the same. Fig. 5 is a cross-sectional view on the line X X of Fig. 4, looking upward. Fig. 6 is a sectional detail illustrating the manner of arranging the stop-guide between the lower-limb section and the slip-socket. Fig. 7 is an enlarged sectional detail of the slip-socket-supporting springs, illustrating the manner of supporting them. Fig. 8 is a rear elevation of the upper part of the lower-limb section and the slip-socket, illustrating a modification in the manner of arranging the slip-socket-supporting springs. Fig. 9 is a cross-sectional view on the line y y of Fig. 8, looking downward. Fig. 10 is a sectional detail illustrating the manner of connecting the slip-socket-supporting springs. Fig. 11 is a rear elevation of the slip-socket removed. Fig. 12 is a rear elevation of the upper portion of the main body-section. Fig. 13 is a perspective view of one of the elastic 40 webbing hook-clamps fast to a section of webbing, and Fig. 14 is a similar view with the webbing removed. Fig. 15 is a perspective view of one end of one of the strips of webbing removed. Fig. 16 is a perspective view from below, and Fig. 17 is a perspective view from above of the bottom plate of the slip-socket detached.

A' is the lower-limb section, preferably cast in one piece, of aluminium, with the walls just 50 thick enough to secure the necessary strength, and hinged at a' to the foot-section in the ordinary manner, as shown.

The body B' of the foot-section is formed of wood, and preferably with an aluminium shell or casing B². The foot-section B' is provided with a cavity a² formed through it, and in which a coiled spring a³ is secured by its ends at a⁴ a⁵ to the wooden body B', and with its center coil extended at a⁶ to form a hook to receive the lower end of a flexible cord or 60 loop a⁷, the upper end of the cord a⁷ being supported by a hook a⁸ on the interior of the lower-limb shell A', as shown. By this simple means the force of the spring a³ is exerted to keep the toe end of the foot-section pressed 65 upward in its normal position and return it to its normal position when released in the act of walking, thus securing the requisite ankle motion.

By arranging the spring a³ in the form of a 70 coil I am enabled to use a much greater length of wire in a very much smaller space than could be used in any other shape, thus securing a much more durable spring than in any other shape.

Formed across the lower-limb section A' at a point above the ankle-joint is a diaphragm or cross-partition A², having an upwardly-working valve b' therein, and with one or more perforations b² through the shell A' below the cross-partitions, so that air-currents are free to pass into the shell A' below the cross-partition and pass upward through the valve b', but cannot pass backward again into the space below the cross-partition, the object 85 to be hereinafter explained.

Surrounding the interior of the shell A', some distance down from the top, is a shoulder d', and fitting into the shell A' above this shoulder is the socket to receive the stump of 90 the severed limb. This socket is formed of the interior portion D', preferably of light wood, and which is fitted to the stump of the severed limb, and the external shell D², which fits the interior of the shell A', and also fits 95 closely on the portion D', as shown, and will be preferably of aluminium, the same as the shell A'.

The two portions D' D² are covered on all sides with buckskin or other suitable soft 100 leather or other substance, as indicated at e, so that all the friction between the shells A' and D² and also between the portion D' and the stump of the severed limb is borne by the

soft covering. The shell D^2 is formed with a shoulder d^2 , corresponding to the shoulder d' , and adapted to rest thereon when the socket is moved downward to a sufficient extent.

5 The portion of the socket below the shoulder d^2 is tapered slightly, and the interior of the projection forming the shoulder a' on the shell A' is correspondingly tapered, as shown in Figs. 4, 6, and 10, so that as the socket is 10 moved downward the parts come together without jar or noise, but with a solid stop when the shoulders come together.

The socket will be provided with means for holding it normally in its upward position, 15 and I have shown two forms of springs to accomplish this result, one to be employed when the amputation is just below the knee and the other when the amputation is near or at the ankle-joint. When the amputation is 20 just below the knee, the lower end of the socket will be provided with a bottom plate E' , having a central perforation g' , and with a ring E^2 upon its upper side, forming a flange and projecting into the lower end of the 25 socket, as shown, and secured in place by rivets or screws.

$g^2 g^3$ are two coiled springs with their ends at $g^4 g^5 g^6 g^7$ projecting laterally and resting beneath the plate E' , and with the central coil 30 of each spring extended laterally in opposite directions, as at $g^8 g^9$, and resting over hooks $g^{10} g^{11}$ on the interior of the shell A' , as shown. The ends of the springs $g^2 g^3$ are supported 35 between ears $g^{12} g^{13}$, projecting downward from the ends of the opening g' , with plugs g^{14} fitting into the ends of the springs and secured in place by screws g^{15} , the plugs being formed with grooves encircling their exteriors to fit the interiors of the wires of the coils, so 40 as to retain them in position. By this arrangement the force of the springs $g' g^2$ is exerted to keep the socket normally in its upward position and return it to its upward position after being released in the act of walking.

45 When the amputation is at or near the ankle-joint, the bottom plate E' cannot be employed, as the stump of the severed limb will project too far down, and in that event 50 I employ springs formed of elastic webbing F' , as shown in Figs. 8, 9, and 10, the upper ends of the webbing being connected to the shell A' and the lower ends being attached to the socket, the spring force of the webbing being 55 exerted to keep the socket normally in its upward position. When this form of spring is employed, the shell A' is provided with elongated slots h' at suitable intervals, one for each spring, through which the webbing 60 operates, cross-bars h^2 being provided at the upper ends of the slots h' to support the upper ends of the webbing.

The ends of the webbing are provided with hooks $h^3 h^4$ to engage with the bars h^2 and 65 with the shoulders d^3 of the sockets $D' D^2$, as shown in Figs. 8, 9, and 10. These hooks $h^3 h^4$ are attached to the webbing in a novel

manner, which is an important feature of my invention.

The hooks are formed of two thicknesses 70 of sheet metal bent over upon itself and spread apart at its lower part to form two plates $h^5 h^6$, embracing the ends of the webbing, the plate h^5 having ears $h^7 h^8$, adapted to be bent over upon the two plates $h^5 h^6$ after the webbing is in place between them. 75

After the webbing is in place between the plates the latter are firmly compressed by any suitable implement and the two plates indented at several points by a sharp-pointed 80 implement to press the metal into the webbing and prevent its removal from between the plates.

The manner of constructing the hooked 85 clasps is more clearly shown in Figs. 13 and 14.

The socket is prevented from turning in the shell A' by forming a blind slot i' in the shell D^2 , and fitting into it a stop i^2 , secured by a screw i^3 to the interior of the shell A' , the slot i' being long enough so that the 90 socket may freely move upward and downward over the stop; but the latter by being attached to the shell A' will prevent the socket from turning in the shell.

m' are holes formed through the shell A' in 95 a circle near its upper end, while similar holes m^2 are formed entirely through all the parts $D' D^2 e$, making the socket, and each perpendicular set of the perforations m^2 are connected on the exterior of the shell D^2 by blind 100 slots m^3 , so that no matter at what point the socket may be there will always be free communication between the holes m' and m^2 . The holes $m' m^2$ and connecting-grooves m^3 105 coact with the valve b' and perforation b^2 to secure a perfect forced ventilation of the stump and the interior of the artificial limb, as will be readily understood.

The stump of the severed limb, being clothed 110 with one or more thicknesses of stocking or sock, fits the socket closely and is at the same time compressible away from the inner surface of the socket, while the exterior of the 115 socket, being covered with buckskin or other soft material, likewise fits the body portion somewhat closely.

The parts being thus constructed, when the 120 stump with its attached socket is drawn upward in the act of walking a vacuum is formed, which the ordinary atmospheric pressure 125 finds easier to overcome by pressing upward the valve b' , which offers a very slight resistance, than to force its way inward against the stocking upon the stump or the leather covering of the socket, which press with some force against the entrances to the passages leading to the exit-holes m' . Then when the 130 stump and its attached socket move downward in the act of walking, a positive piston-like action takes place, and the air, being unable to escape through the now closed valve, forces its way upward between the stocking and socket and escapes through the discharge-holes. By this means a positive and forced

ventilation is secured at each step, which is a very desirable result, especially in warm weather.

Surrounding the shell A' near the top is a metal band G⁷, having ears G² G³ projecting upward and provided on their upper ends with sockets G⁴ G⁵ to form the lower parts of the hinges of the thigh-socket H, the other portions G⁶ G⁷ of the hinges being formed on the lower ends of the side straps G⁸ G⁹, attached to the thigh-socket, as shown.

The ears G² G³ are formed with shoulders n' n², as shown in Fig. 8, to rest upon the upper edge of the shell A', which thus assists in supporting the band and ears in place, so that the downward pressure will be borne principally by the shell A' and not by the rivets or screws securing the band in place. This band by encircling the section A' greatly strengthens it, and also strengthens and supports the knee-joint, especially from side strains.

The valve b' shown is a simple disk moving loosely in a casing; but any other desired form of valve may be employed.

Having thus described my invention, what I claim as new is—

1. In an artificial limb, a body portion having elongated slots therethrough and with a bar across the upper portion of each of said slots, a socket fitting the stump of the severed limb and slidable within said body portion, strips of elastic webbing fitting through said slots and having metal hooks attached to the ends of said elastic webbing and adapted to hook over said cross-bars and beneath shoulders upon said slidible socket, substantially as and for the purpose set forth.

2. In an artificial limb, the body portion having an inwardly-operating valve and with perforations near the top thereof, a socket fitting the stump of the severed limb and adapted to be moved upward and downward within said body portion in the act of walking and having perforations corresponding to the perforations in said body portion, whereby forced ventilation is secured, substantially as described and for the purpose set forth.

3. In an artificial limb, a body portion having an internal shoulder and tapered for a distance below said shoulder, a socket fitting the stump of the severed limb and with its lower portion tapered externally to correspond to the internal tapered portion of said body portion, substantially as described and for the purpose set forth.

4. In an artificial limb, the body portion, a socket fitting the stump of the severed limb and slidable within said body portion, a plate attached to the lower end of said socket and with a central opening and having downward-projecting ears, coiled springs between said ears and with the ends resting beneath said plate and with the central coils extended and supported by hooks to said body portion, substantially as described and for the purpose set forth.

5. In an artificial limb, a body portion having an internal projection, a socket fitting the stump of the severed limb and slidable within said body portion and with a slot fitting over said internal projection on said body portion, whereby said socket while free to move upward and downward within said body portion, will not turn therein, substantially as described and for the purpose set forth.

6. In an artificial limb, a body portion, a band encircling said body portion, ears projecting upward from said band and with one member of the knee hinged upon the upper ends and with shoulders resting on the upper edge of said body portion, the thigh-socket having straps with the other member of the knee-hinge thereon and fitting the hinge members on said ears, whereby the body portion is supported and the downward strains borne by the body portion, substantially as described and for the purpose set forth.

In testimony whereof I have hereunto set my hand in the presence of two subscribing witnesses.

ERICK H. ERICKSON.

In presence of—

LEWIS D. MANN,
C. N. WOODWARD.
